FOREIGN PATENT DOCUMENTS

EM 0022199560020 S 4/2013

Primary Examiner — Rashida C. Walshon(74) *Attorney, Agent, or Firm* — Quarles & Brady LLP(57) **CLAIM**

The ornamental design for a shoe, as shown and described.

DESCRIPTION

FIG. 1 is a top, left, front perspective view of an ornamental design for a shoe;

FIG. 2 is a front elevational view of the shoe of FIG. 1;
FIG. 3 is a rear elevational view of the shoe of FIG. 1;
FIG. 4 is a right side elevational view of the shoe of FIG. 1;
FIG. 5 is a left side elevational view of the shoe of FIG. 1;
FIG. 6 is a top plan view of the shoe of FIG. 1; and,
FIG. 7 is a bottom plan view of the shoe of FIG. 1.

The dash-dash-dash lines are included for the purpose of illustrating portions of the shoe that form no part of the claimed design.
